US00D932096S

(12) **United States Design Patent** (10) **Patent No.:** **US D932,096 S**
Liu (45) **Date of Patent:** **** Sep. 28, 2021**

(54) **ELECTRONIC CIGARETTE**

(71) Applicant: **Tuanfang Liu**, Shenzhen (CN)

(72) Inventor: **Tuanfang Liu**, Shenzhen (CN)

(**) Term: **15 Years**

(21) Appl. No.: **29/724,876**

(22) Filed: **Feb. 20, 2020**

(30) **Foreign Application Priority Data**

Oct. 10, 2019 (CN) 20193055088.2

(51) **LOC (13) Cl.** **27-02**

(52) **U.S. Cl.**

USPC **D27/162**

(58) **Field of Classification Search**

USPC D27/100, 101, 162, 163, 164, 165, 166, D27/167, 168, 169, 170, 171, 172, 173, D27/174, 175, 176, 177, 178, 179, 180, D27/181, 182, 183, 184, 185, 186, 187, D27/188, 189, 190, 191, 192, 193, D28/91.1; D23/360, 362; D24/110, D24/110.4, 110.5, 110.6, 113
